FILE CARD HOLDER

Estil L. Sims, Lake Quivera, Kans.

Filed May 14, 1964, Ser. No. 79,987

Term of patent 14 years

(Cl. D74—2)

Fig. 1.

Fig. 2.

Fig. 3.

Fig. 4.

FIG. 1 is a perspective view of a file card holder, embodying my new design;

FIG. 2 is a top plan view of same;

FIG. 3 is a side elevational view of same; the other side is substantially the same in appearance as this side;

FIG. 4 is an end elevational view of same.

The dotted lines shown in FIG. 3 are for illustrative purposes only.

The design is characterized by the combination of two end members of substantially triangular cross-section with two laterally spaced, relatively wide base elements which connect the end members and define an opening between them, the opening being bridged by two narrower card receiving rails which are also parallel with the base elements and joined at their ends with the end members, the opening having end portions formed as notches in the confronting faces of said end members, all as shown.

I claim:

The ornamental design for a file card holder, as shown and described.
